CONTINUOUS PROCESS OF TREATING OILS

Otho M. Behr, Redondo Beach, Calif., assignor to
Vegetable Oil Products Company, Inc., Los
Angeles, Calif., a corporation of Delaware

Application October 21, 1938, Serial No. 236,228

13 Claims. (Cl. 260—428)

This invention pertains to methods of treating fatty oils such as animal, vegetable and marine oils, in a continuous manner to the end that distinct liquid products be produced therefrom. The invention also relates to means and devices whereby the process may be carried out most effectively.

Substantially all oils are composed in major proportions of compounds of fatty acids with glycerol, such compounds being known as "glycerides". Mono-, di- and tri-glycerides are well known. Since the fatty acids combined with the glycerol will vary greatly in formula and molecular weight, the glycerides also vary materially in molecular weight, molecular size and other properties. For example, the refractive index of an oil increases with the mean molecular weight of the glycerides contained therein.

The fatty acids combined with the glycerol may be either saturated or unsaturated and most oils contain both saturated and unsaturated constituents. The iodine value normally assigned to oils is a measure of unsaturation and is closely associated with the ability of the oil to absorb oxygen and this in turn is indicative of the drying power of the oil. "Drying power" is a relative term but most vegetable, marine and other oils are classified as either drying or non-drying. It may be generally stated, however, that the drying oils are those which contain a very large proportion of the more unsaturated constituents or glycerides whereas non-drying oils contain less highly unsaturated and saturated compounds in major proportion. Linseed oil is an example of a drying oil whereas cottonseed oil is a substantially non-drying oil. Oils containing saturated and less highly unsaturated constituents are usually employed and referred to as edible oils, the more unsaturated oils being generally considered as drying or non-edible.

Attention is here called to the fact that glycerides of oleic acid (which contains but a single double bond) occur in non-drying oils and such glycerides are embraced by the term "less highly unsaturated constituents" or non-drying constituents. Glycerides of linoleic acid, etc., are the more highly unsaturated constituents of drying-oil type but upon polymerization some of these may lose their double bonds in part or even altogether.

Most oils are a mixture of glycerides and such mixture contains both saturated and unsaturated compounds. The resulting oil, therefore, partakes of the properties of both drying and non-drying oils and in many instances such an inter-

mediate oil is unsuited for use either as an edible oil or as a drying oil. The present invention is particularly directed toward the treatment of oils containing a mixture of both saturated and unsaturated glycerides whereby two or more separate and distinct liquid products may be produced, each of these products having properties which render it eminently suited for use in a separate and distinct field.

10 10. Polymerization, condensation or heat-bodying of an oil containing a mixture of both saturated and unsaturated constituents results in molecular unification of the highly unsaturated compounds, thereby producing compounds of larger molecular size and of heavier molecular weight. The saturated or non-drying glycerides do not readily increase in molecular size during polymerization. The present invention contemplates the treatment of partly polymerized oils. By "partial polymerization," reference is made to a heat treatment of an oil to an extent insufficient to completely polymerize all of the constituents of the oil, that is, the polymerization is not carried out to such a point that no further decrease in 15 the iodine value can be subsequently attained by a further polymerisation or heat treatment. Partial polymerization contemplates the condensation or polymerization of highly unsaturated compounds without any material or appreciable increase in the molecular size of the less unsaturated or saturated or non-drying glycerides, such as olein and stearin.

20 20. Generally stated, the present invention is based upon the discovery that a stream of oil containing a mixture of partially polymerized and unpolymerized glycerides (and containing both drying and non-drying constituents) may be subjected to the action of a countercurrent stream of a liquid reagent with the production of liquid solutions, one containing those glycerides of the high molecular weight, large molecular size, whereas the other contains the glycerides of the 25 smaller molecular size and lower molecular weight.

25 25. The two solutions are then treated for the removal of the liquid reagent and products are obtained, one product being eminently suited for use in paints, varnishes, linoleum and wherever a drying oil is desired, whereas the other product is eminently suited for use as a non-drying edible oil as, for example, in hydrogenation, saponification, salad oils, etc. The drying oils obtained as a result of this process are adapted to produce films which are hard, dense, weather-resistant, fast-drying, capable of producing a film of great

tenacity, and further characterized by the property of gelling completely upon being subsequently heated (polymerizing readily and to a further extent under the influence of heat) so as to form a flexible, resinous, irreversible gel. As a result, the liquid products containing the unsaturated drying constituents produced in accordance with this invention can be used as substitutes for Chinawood oil and other expensive products, in the manufacture of varnishes, etc. The other liquid products which are obtained in accordance with this process and containing the saturated, non-drying, edible constituents may be deodorized, neutralized or treated in any other suitable manner without becoming heavy in body, and can then be employed in edible products, soaps, etc.

It will be evident, therefore, that liquid products of enhanced value can be obtained from oils which are of lower quality or which are not particularly well adapted for a particular contemplated use. It may be said that the present invention is an improvement upon the invention disclosed in my co-pending application Serial No. 141,881 filed May 10, 1937.

It is an object of the present invention, therefore, to provide a continuous process of treating various oils such as vegetable, animal or marine oils, in normal or partially polymerized condition, for the purpose of producing liquid products of desired composition, characteristics and properties.

Another object of the invention is to disclose and provide a continuous method of separating an oil containing a mixture of glycerides differing in molecular weight into products having mean molecular weights differing appreciably from the mean molecular weight of the oil originally treated.

A further object is to provide a process of separating in a continuous manner partially polymerized drying oils and unpolymerized non-drying oils from mixtures thereof.

An object of the invention is to disclose and provide a method of producing improved drying oils and improved non-drying oils from mixtures thereof.

A still further object is to provide a continuous method of precipitating polymerized unsaturated constituents from oils containing the same.

An object is to provide means whereby constituents of drying and non-drying types may be separated in a continuous manner from mixtures thereof.

These and other objects, uses, advantages, adaptations and modifications of the invention will be readily perceived by those skilled in the art from the following detailed description of certain exemplary forms of the invention, it being understood that the invention is not limited to the specific examples, materials and products but contemplates numerous changes and modifications coming within the scope of the invention herein disclosed. In order to facilitate understanding, reference will be had to the appended drawing, in which:

Fig. 1 is a diagrammatic representation of one arrangement of elements in which the process of the invention may be carried out.

Fig. 2 is a diagrammatic representation of a modified arrangement of elements in which the process of this invention may be performed.

Although the process is applicable to the treatment of any oil or mixture of oils, the process is of greatest commercial importance in the treat-

ment of semi-drying oils since these oils are available in large quantities and are not well suited for use in paints (or other uses requiring drying oils) nor as an ingredient in food stuffs such as salad oils, shortening, or where non-drying properties are desired. Such semi-drying oils are preferably treated in a partially polymerized state. Soya bean oil is an example of a common semi-drying oil. Such soya bean oils may be polymerized at temperatures of from about 590° F. to 600° F. although temperatures of from about 550° F. to about 610° F. may be used. Polymerization under vacuum is often desirable since an oil of lighter color and lower acid value is thus produced. The heat-bodying or polymerization is conducted in such manner as to cause the minimum amount of gel formation and it is desirable to control the polymerization by observing the drop in iodine value. The iodine value should not be reduced to a minimum but instead the heat-bodying treatment stopped at such point that the oil, at some subsequent time, is capable of exhibiting a further appreciable drop in iodine value upon further heating.

For example, a soya bean oil has been polymerized at a temperature of 590° F. to a viscosity of 90 decipoises. This resulted in raising the refractive index about 80 units, that is, from about 1.4730 to 1.4808 at 50° C. and approximately 50% of the original oil was polymerized. It is to be understood that temperatures of polymerization will vary with the type of oil being treated. For example, soya bean oil requires a higher temperature to obtain the same degree of polymerization as that of hemp seed or linseed oil. In this preliminary partial polymerization the non-drying less saturated glycerides are not increased in molecular size whereas the drying glycerides are polymerized to increased molecular weights and molecular sizes.

The partially polymerized oil is then subjected to countercurrent treatment with a liquid reagent, preferably in what is termed a precipitating tower equipped with baffles, packing rings, or other means for insuring thorough countercurrent contact between the oil and reagent admitted near opposite ends of such tower. The liquid reagent employed should be of a specific gravity differing sufficiently from that of the oil to insure effective countercurrent flow within the precipitating column. The packing should not result in voids so small as to prevent ready downflow of precipitated oil constituents in drop form.

It has been found that the reagent or precipitant is preferably a ketone or a higher alcohol. Dimethyl ketone, methyl ethyl ketone, diethyl ketone and the higher ketones such as diacetone, butyl and amylic alcohols, primary hexyl, secondary amyl, tetrahydrofurfuryl alcohol and other higher alcohols in primary, secondary and tertiary forms, are examples. Alcohols of higher molecular weight (from the group mentioned) give better results than those of lower molecular weight. It has been further found that the aliphatic hydrocarbons, chlorinated aliphatics and aromatics are not effective.

In my co-pending application which specifically described a batch operation, it was stated that four or more volumes of liquid reagent should be added to one volume of the oil being treated. By conducting the process in a continuous manner as herein described, however, materially smaller volumes of reagent may be employed, it being found that as low as one volume of reagent to one volume of oil is capable of

producing desired results provided, however, the process is carried out in such manner that at some point in the treatment an excess of the reagent is present in proportion to the oil.

Referring to Fig. 1, partly polymerized oil from a storage 2 is fed by means of a line 3 to a proportioning pump 4 by which it is supplied and introduced into the upper end of a precipitator 6 through a line 5. The precipitator 6 is preferably supplied with means for controlling the temperature therein as, for example, a jacket supplied with steam, hot water, hot oil, or the like.

Liquid reagent from a storage indicated at 8 is supplied by lines 9 and 10 to the proportioning pump 4 and then introduced in regulated quantity through line 11 into the lower portion of the precipitator 6. Countercurrent flow of the liquid oil and liquid reagent is established within the precipitator 6 and it will be found that a solution of non-drying saturated constituents of the oil in reagent will be discharged from the top of the precipitator 6 as by line 12. As shown in Fig. 1, this solution may then be fed into a still 13 in which separation is accomplished between the reagent and the saturated constituents or glycerides, these being discharged as by line 14 into storage 15 or into any other desired form of apparatus in which they may be deodorized, neutralized or hydrogenated, or otherwise treated. The liquid reagent may be discharged from the still 13 as by line 16 into a condenser 17 and returned to storage through the lines 18 and 19. The product collected in storage 15 will be a bland, non-drying, saturated oil capable of being used for many purposes, such as edible oil, soap manufacture, etc.

The precipitator 6 will also discharge from the bottom and through line 20 a solution of drying glycerides, mostly glycerides of the unsaturated acids of relatively large molecular size and high molecular weight, together with some reagent, the reagent appearing to be in solution in this drying oil. Such solution of drying oil constituents and reagent may then be fed by a proportioning pump 21 and line 22 into the top portion of another precipitator 26. Additional liquid reagent may also be supplied by the proportioning pump 21 from the storage tank 8 and lines 9 and 23 by line 24 into the lower portion of the precipitator 26. Countercurrent flow is again established in this second precipitator, a solution of glycerides and reagent being discharged from the top of the precipitator as by line 27. This solution may then be fed to a still 28, the reagent being discharged by line 29 through a condenser and then returned by line 30 and line 19 into storage. The liquid, oily constituents are discharged from the still 28 as by line 31 into a storage tank 32. The liquid oil collected in tank 32 will be found to have drying properties.

Heavy polymerized constituents together with some liquid reagent will be discharged from the bottom of the precipitator 26 as by line 33 and this solution may then be pumped as by pump 34 and line 35 into the still 36 wherein separation is accomplished between the liquid reagent and the heavy drying constituents of the oil. The reagent will be discharged through the line 37 into a condenser and then returned as by lines 38 and 19 into storage. The heavy drying constituents of the oil, composed primarily of polymerized glycerides of unsaturated acids and characterized by large molecular size and increased molecular

weight, are discharged as by line 39 into the storage 40.

In the process just described and illustrated in Fig. 1 it will be seen that a partially polymerized oil may be converted into three distinct products collected in tanks 15, 32 and 40. Tank 40 will contain a liquid oil having greatly enhanced drying properties and capable of being employed as a substitute for any natural drying oil. In most instances the drying oil collected in the tank 40 will be far superior to any known natural drying oil and will have the desirable drying characteristics referred to hereinbefore. The liquid oil collected in tank 15 will be of the edible, non-drying type. The oil collected in tank 32 will be a drying oil comparable in properties to natural drying oils but it will not have the speed of drying, hardness and tenacity of film which characterizes the product collected in tank 40. Judged by usual standards, however, the product in tank 32 is a good quality drying oil.

As a liquid reagent acetone has been found to be very effective. In carrying out the process with the equipment shown in Fig. 1, the proportioning pump 4 may introduce equal volumes of oil and acetone into the precipitator 6 although it has been found that better results are obtained by the use of from two, two and one-half or three volumes of acetone per volume of oil. The first precipitator 6 may operate at a temperature of from 75° F. to 100° F. and preferably about 90° F., whereas the second precipitator 26 is preferably operated at higher temperatures than those found in the first precipitator. When a temperature of 90° F. is employed in precipitator 6, temperatures on the order of about 130° F. may be employed in precipitator 26 with advantage. The temperatures in the second precipitator, however, should not exceed the boiling point of the liquid reagent used and in the case of acetone should not exceed about 132° F. since the system is not maintained under pressure.

Within the precipitator 6 two separate solutions appear to be formed; one of the solutions formed comprises a solution of glycerides of low molecular weight (non-drying type) dissolved in the liquid reagent, this solution being discharged from the top by line 12. The heavy polymerized drying constituents dissolve in the reagent and are capable of dissolving larger quantities of reagent at higher temperatures. As a result, the solution discharged by line 20 from the bottom of the precipitator 6 is a solution of reagent in drying constituents. Within the precipitator 6 at intermediate points these two solutions appear to be mutually soluble within limits so that all of the constituents of the original oil treated and supplied by line 5 and the reagent form a solution. In the event a heavily polymerized oil is being subjected to the process of this invention, it may be desirable to form a solution of such oil in a part of the total volume of liquid reagent to be used before introducing the oil into the precipitator as by line 5. Additional reagent is then supplied by line 11. The solution of reagent in glycerides discharged by line 20 into the precipitator 26 is preferably treated with reagent (supplied by line 24) in volume sufficient to produce a ratio of not less than about one volume of reagent to one volume of actual oil and preferably a ratio of two to three volumes of reagent to one volume of actual oil, allowance being made for the volume of reagent carried by the oil discharged from the precipitator 6 by line 20.

Furthermore, attention is called to the fact that in commercial operation the amount of oil carried by the reagent discharged from the top of the precipitator 6 by line 12 should preferably not exceed about 20% of the total volume of such outflow.

In a specific example, a partially polymerized semi-drying oil was fed into a precipitator, such as the precipitator 6, at a rate of 0.305 gallon per minute. The precipitator was maintained at a temperature of about 80° F. Acetone was fed into the lower portion of the precipitator at the rate of about 0.757 gallon per minute. The discharge from the top of the precipitator was at the rate of 0.791 gallon per minute and 46% of the total oil fed into the precipitator was discharged through the top conduit (such as the conduit 12), this fraction of oil being in solution in the reagent. Actually, the solution being discharged from the top of the precipitator comprised 18% oil and 82% reagent and the oil had a refractive index of 1.4725.

The oil discharged from the bottom of the precipitator was removed at the rate of 0.271 gallon per minute and this discharge contained 54% of the total oil fed into the system. The discharge from the bottom of the precipitator consisted of 61% oil and 39% acetone. The oil discharged from the bottom of the precipitator had a refractive index of 1.4864.

Attention is called to the fact that the partially polymerized oil originally fed into the precipitator had a refractive index of 1.4800 whereas the two products obtained had refractive indices as stated in the following table:

Sample	Acetone	Oil	R. I. of oil
At overflow	Percent	Percent	
1	82	18	1.4725
2	82	18	1.4737
3	87	13	1.4740
4	89	11	1.4740
5	91	9	1.4750
At discharge	95	5	1.4762
	39	61	1.4864

The samples were taken from top to bottom and are so arranged in the table. Attention is called to the fact that the character of the rising oil in solution at the various levels of the precipitator differed markedly as indicated by the refractive index of the oil.

By referring to Fig. 2 it will be seen that in the modified form of process oil and reagent are fed into the precipitator 6' in a manner similar to that described in connection with Fig. 1. The precipitator 6' is, however, preferably maintained at a higher temperature, that is, at a temperature ranging from say 110° F. to 130° F. It is to be noted that this temperature is below the boiling point or critical temperature of the reagent, in this instance acetone. The solution of the unsaturated non-drying constituents in acetone is discharged from the top of the precipitator 6' as by line 42 into a cooler 43 and then supplied to a separating column 44 provided with suitable means for maintaining a desired temperature in such column. By reducing the temperature of this solution, a part of the constituents of the oil are precipitated in liquid form.

The glycerides precipitated are those of heavier molecular weight. These precipitated glycerides are removed from the bottom of the separator 44 as by line 45 and sent to a still 46 wherein separation is accomplished between the oil and the acetone. The oil is then discharged from

the still as by line 47 into a storage tank 48 whereas the acetone passes by conduit 49 into a condenser 50 from whence it may be returned as by lines 51 and 52 into the acetone storage tank 8'.

Those saturated, low molecular weight, small molecular size glycerides which remain in solution in the acetone are discharged from the top of the separator 44 as by line 54 into a still 55 wherein the acetone is distilled off, permitting the discharge by line 56 of a non-drying saturated oil which may then be collected in the tank 57. The acetone is discharged from the still 55 as by line 58 into a condenser 59 and returned to storage by lines 60 and 52. The heavy unsaturated drying constituents precipitated in 6' are discharged by line 62 into a still 63 wherein by distillation separation is effected between the drying oil and the acetone. The drying oil is discharged by line 64 into the tank 65, the acetone being discharged by line 66 into condenser 67 and then by line 68 back to storage.

In the performance of this process it is to be understood that instead of using a continuous separating column 44, a batch operation may be performed by tank storage cooling.

Although in the examples given three products were produced from the original oil treated, it is to be understood that the process may be employed in the production of two or more separate products from a given oil. Moreover, it is to be noted that the reagent, such as acetone, is recovered and may be used in cyclic operation of the process with very minor losses.

Those skilled in the art will understand that valves, temperature regulating devices and other attachments are appropriately installed in the manner well known to chemical engineers but that such devices have not been shown on the drawing in order to facilitate understanding and prevent confusion.

I claim:

1. In a process of treating vegetable and marine oils, the steps of: introducing an oil having polymerized highly unsaturated drying constituents and unpolymerized non-drying less unsaturated and saturated constituents into the upper portion of a precipitating column; introducing a normally liquid reagent from the group consisting of ketones and butyl alcohol and higher alcohols into the lower end of such precipitating column, at a volumetric rate not lower than the rate at which oil is introduced; continuously withdrawing reagent containing unpolymerized non-drying constituents in solution from the top of said precipitator; continuously withdrawing unsaturated polymerized drying constituents containing reagent in solution from the bottom of the precipitator; and separately purifying each of the withdrawn solutions to produce a liquid oil containing unpolymerized non-drying constituents in major proportion and another liquid oil containing polymerized drying constituents in major proportion.

2. In a process of treating vegetable and marine oils, the steps of: introducing an oil having polymerized drying constituents and unpolymerized non-drying constituents into the upper portion of a precipitating column; introducing acetone into the lower end of such precipitating column at a volumetric rate not lower than twice the rate at which oil is introduced; continuously withdrawing acetone containing non-drying constituents in solution from the top of said precipitator; continuously withdrawing

polymerized constituents containing acetone in solution from the bottom of the precipitator; and separately purifying each of said withdrawn solutions for the removal of acetone therefrom so as to produce two separate liquid oil products.

3. In a process of treating vegetable and marine oils, the steps of: introducing an oil having polymerized drying constituents and unpolymerized non-drying constituents into the upper portion of a precipitating column; introducing a liquid reagent from the group consisting of ketones and butyl alcohol and higher alcohols into the lower end of such precipitating column, at a volumetric rate not lower than the rate at which oil is introduced; continuously withdrawing reagent containing non-drying constituents in solution from the top of said precipitator; continuously withdrawing polymerized drying constituents containing reagent in solution from the bottom of the precipitator; and separately purifying each of the withdrawn solutions.

4. In a process of treating vegetable and marine oils, the steps of: introducing an oil having polymerized drying constituents and unpolymerized non-drying constituents into the upper portion of a precipitating column; introducing a liquid reagent from the group consisting of ketones and butyl alcohol and higher alcohols into the lower end of such precipitating column, at a volumetric rate not lower than the rate at which oil is introduced; maintaining said precipitating column at below the boiling point of the reagent; continuously withdrawing reagent containing a mixture of drying and non-drying constituents in solution from the top of said precipitator; continuously withdrawing polymerized drying constituents containing reagent in solution from the bottom of the precipitator; and separately purifying each of the withdrawn polymerized constituents containing reagent in solution to distillation, and by separately treating the solution withdrawn from the top of the precipitating column by cooling the same to precipitate drying constituents from the remaining solution of non-drying constituents, and then subjecting the remaining solution to distillation to remove reagent therefrom.

5. In a process of treating vegetable and marine oils, the steps of: introducing an oil having polymerized drying constituents and unpolymerized non-drying constituents into the upper portion of a precipitating column; introducing a liquid reagent from the group consisting of ketones and butyl alcohol and higher alcohols into the lower end of such precipitating column, at a volumetric rate not lower than the rate at which oil is introduced; continuously withdrawing reagent containing non-drying constituents in solution from the top of said precipitator; continuously withdrawing polymerized drying constituents containing reagent in solution from the bottom of the precipitator; and separately purifying each of the withdrawn solutions by subjecting the polymerized constituents containing reagent in solution and withdrawn from the bottom of the precipitator to a further countercurrent treatment with additional reagent, and by separately purifying the solution withdrawn from the top of the precipitator.

6. In a method of treating vegetable and marine oils, the steps of: subjecting an oil containing drying and non-drying constituents to partial polymerization; adding a normally liquid reagent from the group consisting of ketone,

butyl alcohol and higher alcohols to said partially polymerized oil to form a solution; introducing such solution into the upper portion of a precipitator; introducing additional reagent from the same group of reagents into the lower portion of the precipitator; maintaining said precipitating column at below the boiling point of the reagent; continuously withdrawing reagent containing non-drying constituents in major proportion from the top of the precipitator; continuously withdrawing a solution containing drying constituents in major proportion from the bottom of said precipitator; and separately purifying each of the solutions so withdrawn.

7. In a method of the character described, the steps of subjecting an oil containing drying and non-drying constituents to partial polymerization; adding acetone to said partially polymerized oil to form a solution; continuously introducing such solution into the upper portion of a precipitator; continuously introducing additional acetone into the lower portion of the precipitator; continuously withdrawing acetone containing non-drying constituents in major proportion from the top of the precipitator; continuously withdrawing drying constituents containing some acetone from the bottom of said precipitator; and separately purifying each of the solutions so withdrawn.

8. In a method of the character described, the steps of subjecting an oil containing drying and non-drying constituents to partial polymerization; introducing such oil into the upper portion of a precipitator; introducing a normally liquid reagent from the group consisting of ketones and butyl alcohol and higher alcohols into the lower portion of such precipitator at a volumetric rate not lower than the rate at which oil is introduced; maintaining said precipitator at a temperature below the boiling point of the reagent; continuously withdrawing reagent containing non-drying constituents in major proportion from the top of the precipitator; continuously withdrawing a solution containing drying constituents in major proportion from the bottom of said precipitator; and separately purifying each of the solutions so withdrawn.

9. In a method of the character described, the steps of subjecting an oil containing drying and non-drying constituents to partial polymerization; introducing such oil into the upper portion of a precipitator; introducing a normally liquid reagent from the group consisting of ketones and butyl alcohol and higher alcohols into the lower portion of such precipitator at a volumetric rate not lower than the rate at which oil is introduced; maintaining said precipitator at a temperature below the boiling point of the reagent; continuously withdrawing reagent containing non-drying constituents in major proportion from the top of the precipitator; subjecting the withdrawn solution to settling at a lower temperature than that in the precipitator whereby drying constituents are precipitated and non-drying constituents remain in solution; removing the precipitated drying constituents from the remaining solution; separately purifying said remaining solution to produce a liquid oil composed essentially of non-drying constituents; and continuously withdrawing drying constituents from the bottom of said first named precipitator.

10. In a process of the character described in claim 12, the further steps of separating reagent from the lower molecular weight glycerides withdrawn from the top of the precipitator by sub-

jecting the withdrawn solution to settling at a lower temperature than that in the precipitator whereby a portion of said glycerides is precipitated and another portion remains in solution in the reagent; and then separating reagent from each portion.

11. In a process of the character described, the steps of: subjecting a solution of a partially polymerized oil comprising a mixture of glycerides varying in molecular weights in a normally liquid reagent from the group consisting of ketones, butyl alcohol and higher alcohols to settling at a reduced temperature in a settling zone, withdrawing glycerides of higher molecular weight from the bottom of the settling zone, 10 withdrawing a solution of glycerides of lower molecular weight from the top of said settling zone, and then separately purifying said solution to remove glycerides therefrom.

12. In a method of the character described, 20 the steps of: introducing a partially polymerized oil comprising a liquid mixture of glycerides varying in molecular weights into the upper portion of a precipitator; introducing a normally liquid reagent from the group consisting of 25

ketones, butyl alcohol and higher alcohols into the lower portion of said precipitator; continuously withdrawing glycerides of higher molecular weights from the bottom of the precipitator, and 5 continuously withdrawing reagent containing glycerides of lower molecular weight from the top of the precipitator.

13. In a process of the character described, the steps of: subjecting a flowing stream of partially polymerized oil containing a mixture of low and high molecular weight glycerides to the action of a countercurrent stream of normally liquid reagent from the group consisting of ketones, butyl alcohol and higher alcohols, in a contact zone, said reagent having a specific gravity differing from that of the partially polymerized oil; maintaining said countercurrent flow at a controlled temperature below the boiling point of the reagent; continuously discharging reagent containing glycerides of low molecular weight in major proportion from the top of said zone, and separately discharging glycerides of higher molecular weight from the bottom of said zone.

OTHO M. BEHR.
